CLAIM

The ornamental design for a ice cream cone cake baking stand/server, as shown and described.

DESCRIPTION

FIG. 1 is a perspective view of our design;

FIG. 2 is a top view of our design;

FIG. 3 is a bottom view of our design

FIG. 4 is a front elevational view of our design, the opposite side view being a mirror image thereof; and,

FIG. 5 is a side elevational view of our design, the opposite side view being a mirror image thereof.
